L. GRUBMAN,
ELECTROMAGNETIC SOUND PRODUCER.
APPLICATION FILED MAY 23, 1914.

1,143,189.

Patented June 15, 1915.

UNITED STATES PATENT OFFICE.

LEO GRUBMAN, OF NEW YORK, N. Y., ASSIGNOR TO ELECTRIC SPARK APPLIANCE CO., INC., OF NEW YORK, N. Y., A CORPORATION OF NEW YORK.

ELECTROMAGNETIC SOUND-PRODUCER.

1,143,189.

Specification of Letters Patent. Patented June 15, 1915.

Application filed May 23, 1914. Serial No. 840,431.

To all whom it may concern:

Be it known that I, LEO GRUBMAN, a citizen of the United States, and a resident of the borough of Brooklyn, county of Kings, 5 city and State of New York, have invented certain new and useful Improvements in Electromagnetic Sound-Producers, of which the following is a specification.

My improvements relate to the type of 10 resonating devices, set forth in my concurrent application No. 825,114, filed Mar. 16th, 1914, in which a diaphragm is caused to vibrate by electro-magnetic means, as for instance in connection with horns for directing sound warnings, and for analogous purposes, the object in the present case being the simplification of structure by eliminating intermediate instrumentalities between the armature and the diaphragm actuated 15 thereby, and the concentration and augmentation of the electro-magnetic force as applied to said armature, as hereinafter more fully set forth; and other incidental features of the invention relating to the specific 20 construction and arrangement of parts described and claimed.

In the accompanying drawings, Figure 1, is a central sectional elevation of an automobile horn embodying the essential features 25 of my invention, parts being shown symbolically; Fig. 2, is a rear view with back casing removed; Fig. 3, is a rear view, the armature and connections being omitted, and the remaining parts being successively broken 30 away to show their relative arrangement.

The horn H, is attached centrally to the annular front plate F, formed with the peripheral flange f. Resting against the rear side of the front plate F, is the spacing pad f', the edges of the elastic resilient diaphragm D, being between said pad f', and a companion spacing pad f''. The inner peripheral edge b, of the back cap or rear casting B, fits within the flange f, of the front 40 plate F, and rests against the rear of the said second spacing pad f''. The electro-magnet M, is also positioned against the said inner spacing pad f'', and is of peculiar construction in that it consists preferably of 45 two annular disks m, m', spaced apart by the annular magnetic block m''. Between the members m, m', of the magnet is the electric coil C, centralized and held in place by a cylindrical tube of insulating material 50 m''. The inner edges of the magnet member

m', adjacent to the diaphragm protrude inward slightly beyond the insulating tube m'', into relatively close proximity to the striking end a, of the armature A, which striking end a, is preferably rounded or dome shaped as shown in Fig. 1, to form an apex 60 for direct intermittent contact with the diaphragm under the impulses imparted by the electrical coil in the usual and well known manner. This rounded or dome shape of 65 the striking face a, of the armature A, admits of the shaping of the inner edges m'', of the magnet plate m', in close conformity thereto, so as to bring them in part virtually 70 between the said face of the armature and the diaphragm as shown in Fig. 1. As a result the armature is brought more fully 75 within the field of magnetic energy created by the coil C, the armature is rendered more responsive, and its power of impact is increased. In this connection it is to be un-present invention consists in positioning the bulk of the armature A, within the central space between the actuating coil and the magnetic poles, and in utilizing the 80 armature itself directly, and without any intervening instrumentality, as the actuating hammer for the diaphragm D. By this means the construction and operation of parts is greatly simplified and rendered 85 more effective, since an intervening plunger or equivalent motion-transmitting device is dispensed with, and the arrangement is rendered more compact, with the armature, to 90 all intents and purposes, positioned practically between the magnetic poles where it is not only influenced by the latter but by the coil also, acting as a solenoid.

As in my concurrent application hereinbefore referred to the armature is mounted 95 upon a retractile spring a', and the "make and break" or current-interrupting means may be essentially the same as in my concurrent application therein set forth, or of any desired or well known construction. 100

The several parts may be secured in position by screw bolts s, s, common to all, as indicated in Fig. 1; and the magnet members m', m'', m'', may if preferred be made in segments instead of continuous annular pieces, 105 without departing from the spirit and intent of my invention in this respect.

It is obvious that the convergent striking face a, of the armature A, may be made conical or of any convergent configuration 110

other than the rounded or dome shape shown in Fig. 1, with like result, so that I do not limit myself in this respect, nor to other non-essential details of construction.

5. What I claim as my invention and desire to secure by Letters Patent is,

1. In electro-magnetic sound producers of the character designated, in combination, an electric coil, a casing of magnetic material 10 inclosing said coil, said casing being formed with a central opening substantially in axial coincidence with the central opening in said coil, a retractile armature of magnetic material positioned mainly in said central space 15 between said coil and casing, and an elastic resilient diaphragm, the armature having its end positioned to directly strike said diaphragm, for the purpose described.

2. In electro-magnetic sound producers of 20 the character designated, in combination, an elastic resilient diaphragm, a retractile hammer-armature of magnetic material having its end positioned to directly strike said diaphragm, and an electro-magnet one pole of 25 which is in close proximity to the portion of the hammer-armature which contacts directly and intermittently with said diaphragm.

3. In electro-magnetic sound producers of 30 the character designated, in combination, an electro-magnet consisting essentially of two parallel disks formed with central openings, an annular spacing block between them, an electric coil positioned between them with 35 its central opening in axial coincidence with the openings in the magnet plates, a retractile hammer-armature of magnetic material positioned mainly within said central space between the magnetic plates and coil, 40 and an elastic resilient diaphragm, the armature having its end positioned to directly strike said diaphragm, for the purpose described.

4. In electro-magnetic sound producers of 45 the character designated, an elastic resilient diaphragm, a retractile hammer-armature of magnetic material having its end positioned to directly strike said armature and formed with a convergent striking face, and 50 an electro-magnet, a portion of which protrudes between said diaphragm and said convergent striking face, said convergent

face positioned within a central opening in said magnet.

5. In electro-magnetic sound producers of 55 the character designated, an elastic resilient diaphragm, an electro-magnet having an electric coil centralized in said magnet, a retractile hammer-armature of magnetic material having its end positioned to directly strike said diaphragm, said end being movable through said magnet and coil.

6. In electro-magnetic sound producers of 65 the character designated, an elastic resilient diaphragm, an electro-magnet having an electric coil centralized in said magnet, a retractile hammer-armature of magnetic material having its end positioned to directly strike said diaphragm, said end being movable through said magnet and coil, 70 and a tube of insulating material centralizing and holding said coil in place.

7. In electric-magnetic sound producers of 75 the character designated, an elastic resilient diaphragm, an electro-magnet having an electric coil centralized in said magnet, a retractile hammer-armature of magnetic material having its end positioned to directly strike said diaphragm, said end being movable through said magnet and coil, the striking face of said armature being rounded and the inner edges of the portion of the magnet adjacent the diaphragm being shaped in close conformity thereto.

8. In electro-magnetic sound producers of 85 the character designated, an elastic resilient diaphragm, a flat coil parallel with the diaphragm, an armature having a portion extending within the coil, and an electro-magnet with one pole on one side of the coil 90 adjacent the diaphragm and the other pole on the other side of said coil.

9. In electro-magnetic sound producers of 95 the character designated, an elastic resilient diaphragm, a single flat coil parallel with the diaphragm, an armature having a portion extending within the coil, and an electro-magnet with one pole on one side of the coil adjacent the diaphragm and the other pole on the other side of said coil.

LEO GRUBMAN.
